CIGAR BANDING MECHANISM

Filed July 22, 1933

UNITED STATES PATENT OFFICE

1,992,760

CIGAR BANDING MECHANISM

Joseph A. Neumair, Hollis, N. Y., assignor to
International Cigar Machinery Company, a
corporation of New Jersey

Application July 22, 1933, Serial No. 681,713

22 Claims. (Cl. 131—61)

This invention relates to banding mechanism, particularly to mechanisms for bunching cigars, and has for its principal objects the improving of such mechanisms to render them more reliable in operation, simpler and more accessible in construction and to produce tighter banding when desired. Thus one of the principal objects of the invention is to produce a simple and reliable liquid applying device for rendering the one end 5 surface of the band adhesive for sealing the band. Another object is to provide a liquid applying device which because of its simple compact structure and small applying element is capable of applying liquid to the band after the band has 10 reached applying position and even after the band has been to some extent partially wrapped around the article, all without interference with the band folding and cigar supporting and conveying parts. Liquid applying mechanism because of its simplicity and compactness lends itself to location near the level of and to the rear 15 of cigar supporting and operative folding parts and thus opens up the machine from the front and above to the operator.

An advantage of the present construction is that since the band in one form of the invention is partially wrapped around the cigar before the applying means acts on the band end, there is less likelihood of the band being displaced and thus 20 misaligned on the cigar. Another object of the invention is to eliminate parts and simplify construction by utilizing the folder as a cooperating element or backstop to hold the band end against the moisture applying element.

It is also a principal object of the invention to provide for lighter banding in mechanisms of the type in which the cigar is held in a conveyor having grippers for holding the cigar at banding position, by locking the grippers in a position affording a tight grip on the cigars so that extra pressure may be used against the cigar by the band applying parts without displacing or bending the cigar.

Still another object of the invention is to provide for more reliable separation of one band from the band above in the stack of bands, by producing a separation of the central portions of the bands through wedging or pressing inwardly the opposite ends of the lower bands to arch the same downwardly in varying degrees. With these and other objects not specifically mentioned in view, the invention consists in certain constructions and combinations which will be hereinafter fully described and then particularly pointed out in the claims hereunto appended.

In the accompanying drawing, in which like characters of reference indicate the same or like parts, Fig. 1 is a front elevation partly in section of the improved cigar banding mechanism; Fig. 2 is a side elevation partly in section of a portion of the mechanism shown in Fig. 1; Fig. 3 is a detail plan view on the line 3—3 of Fig. 2.

Referring now to the drawing, there is shown for purposes of illustration one particular embodiment of the invention. It should be understood however that the means illustrated and referred to in the following description may be varied widely in construction within the scope of the claims, for the particular device selected to illustrate the invention is but one of many possible concrete embodiments of the same. The invention therefore is not to be restricted to the precise details shown and described nor to the particular embodiments chosen as illustrative of the invention.

The invention is illustrated in connection with the wrapping and banding machine disclosed in my application for U. S. Letters Patent Number 629,959, filed August 22, 1932 to which reference is made for details not deemed important to the present invention and therefore not illustrated in the annexed drawing.

The cigar C to be banded is supported in cigar grippers 12 carried by a pair of conveyor chains 11, which grippers 12 are pivoted on pins 13, carried by plates 13a secured to the chains 11 and these grippers are inter-ganged by gear segments 14, one gripper of each set being provided with an operating lever 15. These grippers 12 are normally pressed towards each other to grip the cigar C by fingers 16. The chains 11 are indexed to intermittently forward the cigar step by step from one station to a banding station and thence to another station beyond the banding station and so on, by suitable means such as those disclosed in my application above referred to. At the banding station a stationary cam 17 engages a roller 18 on the arm 15 and locks the grippers in a fixed cigar gripping position holding the cigar against displacement by increased pressure from the band applying parts sometimes used to produce tighter wrapping of the band. The grippers are normally pressed together to yieldingly grip the cigar by spring pressure on the grippers from the spring 19.

The cigar bands B are stacked vertically in a band magazine 20 having opposed end walls engaging the ends of the bands in the stack. At the lower ends of these walls are provided wedging elements or ledges 21 which serve to support the

bands in the stack. These elements 21 have inwardly and downwardly inclined wedging surfaces extending from the end walls 20 at an angle of less than forty-five degrees to the vertical end walls. The inclined surfaces of elements 21 serve to produce an endwise pressure on opposite ends of the lower bands and thus to arch the bands outwardly and downwardly from the stack to separate the central portions of the band.

10 The bands are withdrawn from the magazine one by one by suction arms 22 on a rotating turret 23 which has a vertical band removing movement and a rotary conveying movement produced by means which will now be described.

15 The turret is carried by a shaft 24 and driven step by step through gears 25, 26, 27 and 28 by a Geneva wheel 29 actuated by roller 30 on gear 31 driven from the main drive of the machine through spiral gears 32 and shaft 33. The turret 20 as a whole is given its vertical movement as more fully disclosed in the above mentioned application, by a cam lever 34 mounted on shaft 35 and controlled by a cam roller 36 operated by a suitable cam on shaft 37.

25 The band B is folded about the cigar C by folders 38 supported on arms 39, pivoted on stud 40 secured to slide 41 which imparts vertical movement to the folders through the levers 39 to fold the band along the opposite vertical sides 30 of the cigar. The slide 41 is given vertical movement by a link 42 connected to a lever 43 pivoted on shaft 44 and carrying a roller 45 engaging a cam on shaft 37. The lowermost position of the slide and the band folding parts carried thereby 35 is indicated by dotted lines in Fig. 1.

For the purpose of moistening the band B, there is provided a moistening element 46 in the form of a small roller of yielding moisture absorbing material such as felt, rotatably mounted on a reduced end portion of a carrier bar 47 having reciprocating endwise motion on a bracket 48 slidably mounted on guide rods 49, the reciprocating movement being derived from a bell crank lever 50, pivoted on shaft 37 and actuated by a lever 51 pivoted at 52 and carrying a roller 53 engaging 45 with a cam on shaft 37, said lever 51 being linked by a link 53 with the bell crank lever 50 which in turn is connected by a link 54 to the bracket 48.

50 For the purpose of preventing rubbing of the roller 46 as it passes the liquid supply device now to be described, a moistening wheel 55 supported in a reservoir 56 driven by a shaft 57 is provided which is given a movement toward and away from the path of the bar 47 by a cam 58 resting on a stationary surface 59. The shaft 57 is driven through gears 60 and 61 and a chain 62 from the drive shaft 37. The moistening wheel has its peripheral portion covered with a suitable yielding moisture absorbent material such as felt. 55 The timing of cam 59 is such that the moisture supplying wheel 55 is moved into contact with the moistener roller 46 after the roller has been moved alongside the surface of the wheel 55.

55 For the purpose of yieldingly pressing the moisture applying element 46 against the band B and also for the purpose of permitting it to yieldingly follow the contour of the folder 38 while squeezing the band against the same, as shown in Fig. 2, the bar 47 is pivotally mounted by means of pin 63 on the bracket 48 and is resiliently drawn into band and holder engaging position by a spring 64 anchored to said bar and the bracket 48.

70 After the band has been folded about three sides of the cigar by the vertical movement of the folders 38, the band ends outstanding are over-

lapped by folding means including a roller 65, as disclosed in the above mentioned application, which roller is given movement across the lower side of the cigar in a direction parallel to the direction of cigar movement on the conveyor 11. 5 The folded roller is given this movement by a rack 66 slidably supported by means not shown and actuated by a gear segment 67 engaging teeth on said rack, the gear segment receiving movement from a shaft 68 connected with the main 10 drive of the machine. At the next station of the cigar on the conveyor shown at the right, Fig. 2, there is provided a boss 69 on a plate 70 which serves to maintain sealing pressure on the cigar. At the edge of the plate nearest the banding station a bevelled slot 71 is provided for receiving the roller 65 at which point the roller is withdrawn from contact with the cigar, thus maintaining sealing pressure on the cigar overlap from the banding station to the next station. 15

20 In the operation of the improved banding mechanism the moistening or liquid applying element 46, after receiving moisture from the supply wheel 55 reciprocates to a position underlying the band end at the position in which the band 25 extending straight is clamped between the turret arm 22 and the cigar but spaced below said band end. As the folders 38 move downwardly transversely of the vertical sides of the cigar to lay the band in U formation about the same, the band 30 is forced into contact with the band moistening element and during the continued movement of the folders 38, the curved rear surface 72 of the folder 38 swings the folder away from the cigar against the action of spring 64 and drags the band 35 over said roller which due to its rotatable mounting is in rolling contact with the band. It is noted that since the band is clamped against the cigar and partially wrapped around the same prior to moistening, there is no chance for the 40 band to be displaced by the engagement of the moistening element with the band. It is also noted that due to the location and movement of the moistening mechanism to the rear of and below the turret, the operator of the machine who 45 is ordinarily to the left of the machine as shown in Fig. 1, has easy access to the band applying elements and to the cigar.

What is claimed is:

1. In a cigar banding machine, the combination with a cigar support, of means for wrapping a band around three sides of the cigar with the ends outstanding, means for folding said outstanding ends on the remaining side of the cigar, and mechanism for applying liquid to one end of the band while the band is being wrapped around said three sides. 50

2. In a cigar banding machine, the combination with a cigar support, of means for wrapping a band around three sides of the cigar with the 60 ends outstanding, means for folding said outstanding ends on the remaining side of the cigar, and mechanism for applying liquid to one end of the band while the band is being wrapped around said three sides, said mechanism including devices having a to and fro movement for moving a liquid carrying element against the band end during the said wrapping. 65

3. In a cigar banding machine, the combination with a cigar support, means for holding a 70 band transversely of the cigar, band applying means for wrapping the band about three sides of the cigar into U formation, and liquid applying means providing an operating element movable endwise alongside said support in and out 75

with a conveyor carrying sets of coacting grippers for supporting and carrying articles to a wrapping position, yielding means pressing one gripper of a set towards the other to yieldingly grip the article, wrapper applying means for operating on the articles, means for locking said grippers in fixed article gripping position during the wrapping operation, said means comprising an arm carried by said conveyor and connected to said grippers operable to hold the same closed on the article, and means off the conveyor arranged to operate said arm.

18. The combination with conveyor means for intermittently moving articles from one station to another, of band applying means for wrapping a band around the article and overlapping the ends of said band at one station, said band applying means including a folder having movement parallel to the direction of movement of said conveyor to lay the last folded end of the band over the other end of the band, and means for giving said folder movement with the article substantially to the next station to maintain pressure on the overlap during said movement.

19. The combination with conveyor means for intermittently moving articles from one station to another, of band applying means for wrapping a band around the article and overlapping the ends of said band at one station, said band applying means including a folder having movement parallel to the direction of movement of said conveyor to lay the last folded end of the band over the other end of the band, and means for giving said folder movement with the article substantially to the next station to maintain pressure on the overlap during said movement, a plate having a boss arranged to exert pressure on the band overlap at said next station and folder operating means coacting with said plate to cause the folder to withdraw from contact with the

cigar band substantially at the point where the boss begins to exert pressure on the overlap.

20. In a banding machine, the combination with a support for an article, of means for supplying bands and folding them around the article, and a liquid applying means cooperating with said means to render one end of the band adhesive, said applying means comprising a carrier bar, a liquid retaining element on said bar adjacent the end thereof, a source of supply of liquid, and means for giving said bar reciprocating endwise movement alongside said support from said source of supply to band engaging position.

21. In a banding machine, the combination with a support for an article, of means for supplying bands and folding them around the article, and a liquid applying means cooperating with said means to render one end of the band adhesive, said means comprising a carrier bar, a liquid retaining element on said bar adjacent the end thereof, a source of supply of liquid, and means for giving said bar reciprocating endwise movement alongside said support from said source of supply to band engaging position, said liquid retaining element consisting of a roller of yielding liquid absorbent material arranged on said bar for rolling contact with said band.

22. In a cigar banding machine, the combination with a support for a cigar, of means for supplying bands and folding them around the cigar, and a liquid applying means comprising a liquid retaining element, of a liquid supply device having a moistened surface, means for giving said element a to and fro movement alongside said support from band engaging position to a position alongside said surface but separated therefrom, and means for giving said element and device relative movement transversely to the direction of said to and fro movement to bring them into engagement.

JOSEPH A. NEUMAIR.
